UNITED STATES PATENT OFFICE.

FRANK W. ROBINSON, OF READING, PENNSYLVANIA, ASSIGNOR TO THE NOLDE & HORST CO., OF READING, PENNSYLVANIA, A CORPORATION OF PENNSYLVANIA.

STRIPING MECHANISM FOR KNITTING-MACHINES.

1,357,254.

Specification of Letters Patent.

Patented Nov. 2, 1920.

Application filed April 14, 1919. Serial No. 289,844.

To all whom it may concern:

Be it known that I, FRANK W. ROBINSON, a citizen of the United States, residing at the city of Reading, in the county of Berks 5 and State of Pennsylvania, have invented certain new and useful Improvements in Striping Mechanism for Knitting-Machines, of which the following is a specification.

10 My invention relates to circular knitting machines comprising suspended striping-thread fingers and means for imparting needle-engaging swings to said fingers; and it consists in the improved mechanism for 15 limiting such swings which is fully described in connection with the accompanying drawings and the novel features of which are specifically pointed out in the subjoined claims.

20 Figure 1 is an elevation of my improved striping attachment with its relation to the known knitting machine structure very simply indicated.

Fig. 2 is a sectional plan view on the line 25 2—2 of Fig. 1; and Fig. 3 a similar view on the line 3—3 thereof.

Fig. 4 is a diagrammatic view showing several adjacent fingers and swing-limiting means operative thereon respectively above 30 and below their points of suspension; the small dotted circles indicating different positions to which the upper finger stops may be adjusted.

Figs. 5, 6 and 7 are diagrammatic views 35 indicating the respective effects of adjusting the upper swing-limiting mechanism to the several positions indicated in Fig. 4.

The drawing indicates the usual circle of knitting needles 3, and a fixed machine 40 bracket 4 carrying a centrally depending post 5 to which the suspension plate 10 for the striping-thread carrier fingers 11 is secured. Each of these fingers is independently suspended in a socket bearing 12 on 45 said plate, and is arranged to have a needle-engaging swing imparted to its free thread-guide end 13; this being effected, as shown, by an operating cam 14 set to contact with rollers 15, 16 on an arm 17 and a branch 50 arm 19 respectively of each spring-tensioned finger, in the manner fully set forth in my prior Patent No. 1,203,131, issued October 31, 1916.

My improved construction as shown, em- 55 ploys a closely arranged circular series of

striping-thread fingers 11 so as to enable the simultaneous forming of a large number of parallel stripes, and in connection therewith, swing-limiting means which permit of advantageously varying the stripes notwithstanding close spacing of the fingers.

Each of the fingers employed is provided with an upward extension 25 beyond its point of suspension in socket bearing 12; said extensions varying however, on adjacent 60 fingers as shown in Fig. 4, where the extension of the middle finger is made longer than the adjacent ones and is also formed with an enlarged end portion 26 and a reduced portion 27 below the latter, either of 65 which portions is adapted to coöperate with the movable swing-limiting mechanism hereinafter described.

To provide for securing variability of the 70 needle-engaging swings of the fingers where- by a complete series of uniform stripes or differing stripes in determined groups may be produced, I employ coöperatively separate 75 swing-limiting mechanisms acting respectively upon the lower portions of the fingers 80 and upon the different upward extensions 25 thereof. The lower swing-limiting means comprises oppositely extending finger stops 30, 31 secured in independently adjusted positions between adjacent fingers 11, 11, so as to 85 respectively limit the swing of the latter toward the rigid stop-support 32 which is located between said fingers. These stop-supports 32, as shown, form inverted posts on the suspension plate 10, depending between 90 each finger and the adjacent ones on either side, so that the swing of each finger in each direction may be accurately limited as desired by independent adjustment of the 95 respective stops 30, 31.

The separate swing-limiting mechanism which operates upon the finger extensions 100 25, comprises a stop-carrier ring 35 centrally mounted above the suspension plate 10 and vertically adjustable by means of a suitably operated carrier arm 36. Radiating spokes 37 on this ring, extending between the finger extensions 25, are each provided with independently adjustable oppositely extending stops 38, 39 adapted to contact with the 105 upper portions of said extensions so as to limit the finger swings as determined by the separate setting of said stops 38, 39, and their joint positioning by adjustment of the movable carrier ring 35; the lower swing- 110

limiting stops 30, 31 however becoming effective as determined by the adjustment of said ring 35, as will be understood by reference to Figs. 4 to 7.

5 Fig. 4 shows the lower finger-stops 30, 31 fixedly set as required to produce determined needle-engaging swings whenever the fingers, or certain of them, are uncontrolled by the upper finger-stops 38, 39 of the adjustable carrier ring 35. The latter is shown in an intermediate position; but small circles 38^a, 39^a above, and 38^b, 39^b below, indicate other positions to which the attached finger-stops are jointly moved by adjustment of the 10 carrier ring 35.

20 Figs. 5, 6 and 7 indicate diagrammatically the several needle-engaging swings produced by the upper, intermediate and lower adjustments respectively of the carrier ring 35 as indicated in Fig. 4; Fig. 5 showing that no swing is imparted to the middle finger, while the swing of the adjacent finger is limited only by the fixed lower stops 30, 31; Fig. 6 also showing no swing imparted to the 25 middle finger, but the swing of each adjacent finger reduced to a minimum; and Fig. 7 showing medium swings imparted to the outer fingers as determined by the upper stops, while the swing of the middle finger 30 is limited only by the lower stops therefor.

35 It will be readily understood that a further upward adjustment of the carrier-ring 35 would leave all the needle-engaging finger swings under control of the lower stops alone; that different formations of the upward finger-extensions 25 would vary the swinging effects particularly set forth; and that proper adjustment of the carrier ring 35 during the knitting of a striped fabric 40 enables the production of desired ornamental breaks or variations in the several stripes. The construction specifically set forth may be readily modified within the invention as defined in the claims.

45 What I claim is:—

1. A circular knitting machine comprising a circular series of independently suspended striping-thread carrier fingers each of which has an upward extension beyond its point of 50 suspension; means for imparting needle-engaging swings to the thread-guide ends of said fingers; and separate means for limiting said needle-engaging swings operative upon

said fingers respectively above and below their suspension points.

55

2. A circular knitting machine comprising a circular series of independently suspended striping-thread carrier fingers each of which has an upward extension beyond its point of suspension; means for imparting needle-engaging swings to the thread-guide ends of said fingers; means operative upon said fingers below their suspension points for determinedly limiting their needle-engaging swings; and means operative upon said fingers above their suspension points for differently limiting their needle-engaging swings; said last-named means being movable to operative or inoperative position.

60

3. A circular knitting machine comprising a circular series of independently suspended striping-thread carrier fingers each of which has an upward extension beyond its point of suspension such extensions having varied cross-sections; means for imparting needle-engaging swings to the thread-guide ends of said fingers; and stopping means adjustably operative upon different points of said upward finger extensions to determinedly limit the needle engaging 80 swings.

75

4. A circular knitting machine comprising a circular series of independently suspended striping-thread carrier fingers each of which has an upward extension beyond its point of 85 suspension but said extensions being different; means for imparting needle-engaging swings to the thread-guide ends of said fingers; and stopping means for limiting said swings which are jointly movable longitudinally of said extensions to vary the limiting contact therewith.

90

5. A circular knitting machine comprising a circular series of independently suspended striping-thread carrier fingers; means for 95 imparting needle-engaging swings to the thread-guide ends of said fingers; and rigidly supported posts depending between adjacent fingers and each provided with separate stops for limiting the swing of the 100 respective needles toward said post, said stops being rigidly fixed to said posts in transversely adjustable relation thereto.

In testimony whereof I affix my signature.

FRANK W. ROBINSON.
